UNITED STATES PATENT OFFICE.

WALTER E. KEACH, OF CUMBERLAND, RHODE ISLAND.

DESIGN FOR LACE EDGING.

No. 40,018.

Specification for Design.

Patented May 25, 1909.

Application filed March 19, 1909. Serial No. 484,584. Term of patent 7 years.

To all whom it may concern:

Be it known that I, WALTER E. KEACH, a citizen of the United States, residing at Cumberland, in the county of Providence and State of Rhode Island, have invented a new, original, and ornamental Design for Lace Edging, of which the following is a specification, reference being had to the accompanying drawing, forming part thereof.

The figure is a plan view of the lace edging showing my design.

I claim:

The ornamental design for lace edging, as shown.

WALTER E. KEACH.
